UNITED STATES PATENT OFFICE

TOWNSEND PALMER, OF MIDDLETOWN, CONNECTICUT

DESIGN FOR A HAMMOCK FABRIC

Application filed May 26, 1931. Serial No. 39,978. Term of patent 14 years.

To all whom it may concern:

Be it known that I, TOWNSEND PALMER, a citizen of the United States, and a resident of Middletown, in the county of Middlesex and State of Connecticut, have invented a new, original, and ornamental Design for a Hammock Fabric, of which the following description, in connection with the accompanying drawing, is a specification.

The figure of the drawing is a plan view of a piece of hammock fabric showing the design. The detailed illustration is carried forward throughout the extent of the fabric.

I claim:

The ornamental design for a hammock fabric as shown and described.

In testimony whereof, I have signed my name to this specification.

TOWNSEND PALMER.
